[57] CLAIM

The ornamental design for a stirrup, as shown and described.

DESCRIPTION

FIG. 1 is a perspective view taken from the rear and right of a stirrup showing my new design;

FIG. 2 is a perspective view taken from the rear and bottom thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a rear elevational view thereof in a released position, wherein the footplate portion of the stirrup has been rotated about the hinge in order for its front to be viewed; and,

FIG. 9 is another perspective view thereof in a released position.
